CLAIM

The ornamental design for a can end, as shown and described.

DESCRIPTION

FIG. 1 is a top perspective view of a can end showing my new design;

FIG. 2 is a bottom perspective view thereof;

FIG. 3 is a top plan view thereof;

FIG. 4 is a bottom plan view thereof;

FIG. 5 is a back side view thereof; and,

FIG. 6 is a right side view thereof.

The lines on the can end illustrate shading and contour of the surface.
